RUSSELL D. BEERBOWER, OF FORT WAYNE, INDIANA

MECHANICAL TOY

Application filed June 27, 1932. Serial No. 619,414.

This invention relates to improvements in mechanical toys in which a configuration is animated by operation of a torsion wheel. One of the objects of the invention is to provide a simple expedient that is readily attachable to the operating cord for a torsion wheel by means of which a configuration when applied thereto is animated upon operation of the torsion wheel. A further object is to provide a configuration and operating means therefor so constructed that derangement thereof while operated normally is circumvented.

An illustrative embodiment of the invention is shown in the accompanying drawing, in which:—

Fig. 1 is a side elevation of a structure in which the invention is embodied, a portion being broken away;

Fig. 2 is a front end elevation of a toy aeroplane constituting a part of the embodiment;

Fig. 3 is a fragmentary side elevation of the actuating spiral for the aeroplane;

Fig. 4 is an inner end view of the actuating spiral;

Fig. 5 is a cross section of Fig. 3 on the line 5—5 thereof;

Fig. 6 is a fragmentary top plan of the aeroplane and actuating spiral; and

Fig. 7 is an end view of a torsion wheel provided with a sound making rim.

The illustrative embodiment of the invention consists of three co-operative members: A torsion wheel 1 and its complemental operating cord 2; a configuration 3; and an actuating spiral 4 for the configuration.

The torsion wheel 1 is in the form of a circular disc provided with an axial opening 5 in which is inserted a plug 6 by which the cord 2 is secured to the wheel. The cord 2 constitutes the operating means for the wheel as in the form of an endless band which is secured in the wheel with its middle portions thereof disposed in diametrically opposite positions respecting the plug 6 at points equally spaced from the axis of the wheel so that two loops 7 and 8 of the cord are provided that extend oppositely from the wheel. Rotary movement is imparted to the wheel alternately in opposite directions in the usual

manner by engaging the outer ends of the loops with the thumbs inserted therethrough and then alternately applying tension and slack to the cord as the wheel revolves.

Preferably, the wheel is provided with a sound making member consisting of an elastic rim 9 that is of sufficient breadth as to extend axially from each end of the wheel so that corresponding flanges 10 are formed. In each flange are made numerous slits 11 which permit the intervening segments 12 of the flanges to spread radially outward by influence of centrifugal force developed by rotation of the wheel, whereupon a whizzing sound is produced.

The configuration 3 may be of a form such as to simulate an aeroplane or any other object to suit individual fancy, the aeroplane shown in the drawing being merely exemplary. The frame 13 of the aeroplane preferably is made of sheet metal shaped so as to have an elongated transversely arched top 14 with a boss 15 upon which is suitably secured a wing 16. On the forward end of the frame is secured a head 17 preferably formed of sheet metal and so shaped as to present the appearance of cylinders 18 and propeller blades 19 of an aeroplane motor. In the axial portion of the head 17 is made a slot 20 and those portions 21 of the head contiguous with the sides of the slot are oppositely depressed so as to extend substantially parallel with each other and diagonal with respect to the axis of the head.

The actuating spiral 4 is preferably made of spring wire formed into a coil of uniform turns spaced apart as an open coil spring. The last coil 22 at one end of the spiral is closed at its end which bears against the coil 23 adjacent thereto.

Adjacent the opposite end of the spiral are formed several close coils 24, the innermost one being connected to the next adjacent open coil 25 by an axial portion 26 of the wire forming the spiral which projects forwardly to a point within the close coil adjacent thereto. Contiguous with the outermost coil 24 is formed an elongated spring loop 27 that extends across the axis of the actuating spiral through which one of the loops 8 of the op-

erating cord is loosely strung when positioned axially through the spiral. The spiral is disposed so as to extend loosely through the slot 20 in the head 17 of the aeroplane as does also 5 the cord 2 forming the corresponding loop 8 so that upon rotation of the spiral the aeroplane is moved forward or backward as the spiral is revolved upon its axis alternately in opposite directions.

10 When the aeroplane is in position upon the actuating spiral the rear end of its frame is confined in operative position by means of a transversely disposed pin 28 therein that extends beneath the spiral so that the frame 15 is prevented from dislodgment.

In operation, the loops are grasped by the operator and manipulated in the usual manner in operating an ordinary torsion wheel. As the wheel rotates first in one direction 20 and then in the other the cords of the loops entwine correspondingly, and alternately in opposite directions, and the spiral is likewise revolved thereupon causing the aeroplane to travel to and fro lengthwise along the spiral.

25 When the foremost open coil 25 passes completely through the slot 20 the axial portion 26 then extends in the slot and further forward progress of the aeroplane is prevented by contact of the head 17 with the adjacent 30 close coil 24 which constitutes a stop for limiting forward movement of the configuration, whereupon the spiral rotates idly. When rotation of the actuating spiral is reversed and the loop 8 of the operating cord is held lower 35 than the loop 7 the open coils follow successively through the slot 20 causing the aeroplane to travel rearwardly, and is again moved forwardly upon the succeeding reciprocal movement of the spiral.

40 The sound produced by the slit flanges on the revolving torsion wheel appeals to the imagination of the observer and conveys the impression of the sound created by an aeroplane in flight which adds realistic value to the toy.

45 I claim:—

1. A toy consisting of a torsion wheel and its complemental operating cord, an elastic rim on said wheel provided with axially extending slit flanges adapted to create sound upon operation of the wheel, an actuating spiral having an open coil portion and a stop operatively disposed upon said cord so as to be revolved thereby upon its axis when the wheel 50 is actuated, and a miniature configuration of an aeroplane engaged by said spiral so as to be moved to and fro thereby upon rotation of the spiral alternately in opposite directions and its movement limited by said stop.

55 2. A toy consisting of a torsion wheel and its complemental operating cord, an actuating spiral having an open coil portion, one end of said spiral having an axial portion and close coils constituting a stop, the coil at the 60 opposite end of said spiral being closed, a

loop adjacent the outer end of said stop, the opening through which extends transversely with respect to said spiral, said spiral being disposed in operative relation with said cord so that one of the end portions thereof 70 extends loosely through said loop and lengthwise through said spiral, and a configuration engaged by said spiral so as to be actuated thereby upon rotation of the spiral alternately in opposite directions and its movement limited by said stop.

3. A toy consisting of a torsion wheel and its complemental operating cord, means operatively related with the wheel adapted to create sound upon rotation thereof, an actuating spiral disposed on said cord so as to be revolved thereby upon its axis when the wheel is actuated, and a miniature aeroplane engaged by said spiral so as to be moved to and fro thereby upon rotation of the spiral 85 alternately in opposite directions.

4. A toy consisting of a torsion wheel and its complemental operating cord, an elastic rim on said wheel provided with slit flanges adapted to create sound upon rotation of the 90 wheel, an actuating spiral operatively disposed on said cord so as to be revolved thereby upon its axis when the wheel is actuated, and a configuration engaged by said spiral so as to be moved to and fro thereby upon rotation of the spiral 95 alternately in opposite directions.

5. A toy consisting of a torsion wheel and its complemental operating cord, an actuating spiral operatively disposed on said cord 100 so as to be revolved thereby upon its axis when the wheel is actuated, and a configuration engaged by said spiral so as to be moved to and fro thereby upon rotation of the spiral alternately in opposite directions.

In testimony whereof I affix my signature.
